CLAIM

I claim the ornamental design for a transparent drinking vessel with metallic core and lid, as shown.

DESCRIPTION

FIG. 1 is a perspective view of the transparent drinking vessel with metallic core and lid.

FIG. 2 is a partially exploded side elevation view of the transparent drinking vessel with metallic core and lid showing the vessel and the lid;

FIG. 3 is a bottom view of the transparent drinking vessel with metallic core and lid; and,

FIG. 4 is a top view of the transparent drinking vessel with metallic core and lid.

FIG. 5 is a cross section of the drinking vessel taken through line 5-5 of FIG. 2.
